UNITED STATES PATENT OFFICE.

GEORGE A. THOMAS AND CONRAD HEBERER, OF VALERIA, IOWA, ASSIGNEES OF ONE-
THIRD TO ATHELBERT H. HEBERER, OF MINGO, IOWA.

SHINGLER'S CHAIR.

1,113,068.

Specification of Letters Patent.

Patented Oct. 6, 1914.

Application filed August 20, 1913. Serial No. 785,679.

To all whom it may concern:

Be it known that we, GEORGE A. THOMAS and CONRAD HEBERER, citizens of the United States, and residents of Valeria, in the county of Jasper and State of Iowa, have invented a certain new and useful Shingler's Chair, of which the following is a specification.

The object of our invention is to provide a shingler's chair of simple, durable and inexpensive construction, adapted to be secured to shingles and to the boards of the roof of a house quickly and easily.

More particularly, it is our object to provide such a device which can be secured to a shingle which has been nailed on a roof and to the roof in such a manner that no holes are made in any of the shingles and without the use of special tools, nails, bolts or the like.

Still a further object is to provide such a device in which the seat of the chair may be arranged in substantially horizontal position regardless of the pitch of the roof upon which the shingler may be working.

Still a further object is to provide such a device having a fastening means and an adjustable seat so secured thereto that after the device is installed and it is desired to remove it, the seat may be grasped in one hand and moved to position for releasing the fastening device.

Our invention consists in certain details, in the construction, combination and arrangement of the various parts of the device, whereby the objects contemplated are attained, as hereinafter more fully set forth, pointed out in our claims and illustrated in the accompanying drawings, in which

Figure 1 shows a top or plan view of a shingler's chair, embodying our invention.

Fig. 2 shows a side elevation of the same installed on a roof. Fig. 3 shows a rear elevation of the same. Fig. 4 shows a detail, sectional view of the means for locking the chair in position on the roof.

In the accompanying drawings, we have used the reference numeral 10 to indicate generally a plate having its forward edge sharpened at 11 and having at its lower end downwardly extending teeth 12. Secured to the upper surface of the plate 10, near its forward sharpened edge 11 is a bracket 13 in which is centrally pivoted a bar 14 which has formed on its forward end downwardly

extending teeth or points 15 designed to engage a shingle or the like between said teeth and the plate 10. At its rearward end the bar 14 is provided with bifurcated arms 16, for supporting a frame bracket 17, shown in dotted lines in Fig. 1, which supports a seat 18 which may be of wood or other suitable material. Formed on the forward end of the frame 17 is a forward projection or extension 19, having bifurcated arms 20 which are pivoted between the arms 16 by means of a bolt 21. Pivoted on the bolt 21, between the arms 20 is a cam shaped plate 22, mounted off center on a bolt 21 and provided with projections 23 and 24 near its lower and upper edges at its rear end, so arranged as to permit considerable play of the extension 19 and to be engaged by the extension 19 when said extension is moved toward the upper or lower limits of its movement. The plate 22 is so arranged that when the plate 10 is in position upon a roof and the seat 18 is raised to substantially vertical position the projection 24 will be engaged by the portion 19 so that a thin portion of the plate 22 will be between the bolt 21 and the plate 10 permitting the rearward part of the bar 14 to be brought close to the plate 10 and allowing the forward end of said bar to be raised away from the plate 10. The sharp edge 11 may then be pushed under the shingle, as shown in Fig. 2. The seat 18 may then be lowered to substantially horizontal position. As the seat 18 is lowered the member 19 engages the projection 23 and moves the plate 22 until its thicker portion is between the bolt 21 and the plate 10, thereby raising the forked arms 16 with relation to the plate 10, and lowering the points 15 with relation to said plate until said points engage and enter the shingle 24. A sharp blow will drive the points 12 into the shingles on the roof.

Pivoted to the frame 17 are legs 25, having sharp pointed ends 26 which enter the roof or shingles when the seat 18 is moved to proper position and some downward pressure is put upon the legs 25.

When it is desired to remove the chair from any position where it has been fastened, the seat 18 is raised, thereby moving the cam plate 22 until the arms 16 may be lowered with relation to the plate 10 and the pointed members 15 disengaged from the shingle 24 to which they have been secured.

The chair may then be replaced in any other position.

It will be seen that the device may be readily and quickly secured to a roof after a few shingles have been laid, without driving any nails through any of the shingles and we are therefore able to do away with the holes which are made through the shingles which admit moisture when the ordinary method of laying shingles by using a 2x4 for a foot hold is employed.

The shingler's chair may be quickly and easily secured in position without the use of special tools and without any bolts or detachable parts. The parts of our device are of simple and inexpensive construction and the whole chair may be made of such durable material as to make the device practically everlasting. The parts are accurate in their working and cannot readily get out of order.

It will be understood that we intend to cover by this application any changes in the details of the construction of our device which may be included within the scope of the appended claims.

We claim as our invention:

1. In a device of the class described, a plate having one edge designed to be inserted under a shingle or the like, an arm pivoted between its ends, and having a sharp downward extension at one end, spaced above the plate near the edge above mentioned, a seat supporting bracket pivoted to

the other end of said arm, a cam pivoted to said arm and to said bracket, said cam being provided with a concave portion, said bracket being arranged with a portion extending into said concave portion and of such size as to permit considerable movement of said portion within the concave portion and to engage said cam above or below said concave portion when said bracket is moved to the respective limits of its movement within the concave portion, for thereby moving said cam.

2. In a device of the class described, a plate having one edge designed to be placed beneath a shingle or the like, a bar pivoted between its ends above said plate, and having on one end a downward extension designed to extend above said plate near the edge above described, a bracket, a cam, means for pivoting said bracket and cam to the other end of said bar, said cam being provided with a concave portion, said bracket having a portion received within said concave portion and capable of limited movement therein, and designed to engage said cam at each extreme of said movement.

Des Moines, Iowa, August 5, 1913.

GEORGE A. THOMAS.
CONRAD HEBERER.
